Patented Feb. 21, 1967

207,039

SOAP TABLET OR THE LIKE

Edmund James Cliffe Sillett, Maidenhead, England, assignor to Lever Brothers Company, New York, N.Y., a corporation of Maine

Filed Mar. 23, 1964, Ser. No. 79,123

Claims priority, application Great Britain Sept. 25, 1963

Term of patent 14 years

(Cl. D73—1)

FIG. 1.

FIG. 2.

FIG. 3.

FIG. 4.

I claim:

The ornamental design for a soap tablet or the like, substantially as shown.
